UNITED STATES PATENT OFFICE

NORTON A. NEWDICK, OF COLUMBUS, OHIO

LOADING MACHINE

Application filed February 5, 1929. Serial No. 337,718.

This invention relates to an improved loading machine, designed particularly for the operation of effecting mechanically the transference of coal from the working faces of 5 underground mines into cars suitable for the removal of the coal from the mines.

As is well known, coal in its native beds is found in strata of varying thickness, the strata ranging in most commercial mines 10 from four to ten feet in thickness, and it is a primary object of the present invention to provide a loading machine which, from a manufacturing standpoint, may be stand-ardized throughout practically its entire con-15 struction, but wherein features of design are present which, by slight structural substitu-tions and adjustments, adapt the machine to coal seams of any thickness and to the vary-ing equipment used in connection therewith. 20 This application is filed in lieu of my aban-doned case Serial No. 688,343, filed January 24, 1924.

With these and other objects in view that will appear as the description proceeds, the 25 invention further consists in the novel fea-tures of construction, combinations of ele-ments and arrangements of parts, hereinafter fully described and particularly pointed out in the appended claims. In the accompan-30 ying drawings, forming a part of this speci-fication, and in which similar reference char-acters denote like and corresponding parts throughout the several views thereof:

Figure 1 is a side elevation of the loading 35 machine comprising the present invention,

Figure 2 is a top plan view thereof,

Figure 9^a is a detail view thereof,

Figure 10 is a vertical transverse sectional view on the line 10—10 of Figure 3.

Figure 11 is a horizontal sectional view 60 taken through the clutch and gear reduction transmission of the machine,

Figure 12 is a plan view of the automatic reverse mechanism,

Figure 13 is a horizontal sectional view 65 taken through said reverse mechanism,

Figure 14 is a plan view of the pony truck used in supporting the forward end of the gathering conveyor for travel,

Figure 15 is a sectional view taken on the 70 line 15—15 of Figure 14.

In the accompanying drawings the load-ing machine is illustrated as consisting of a truck or other traveling base, which in this instance is adapted for travel over the stand-ard track-way 1 of a mine. The truck has

mounted on the forward end thereof a gath-er-75 ering conveyor arranged to sweep horizon-tally across the floor surface of a mine and

to gather, in its path of travel, all loose ma-80 terials lying on the mine floor in the range of sweeping movement of the gathering con-veyor.

By means of the gathering conveyor the coal is removed from the mine floor and is elevated to a point above the truck, at 85

which point it is discharged from the gath-er-85 ering conveyor and is deposited within a wide open mouthed hopper of the delivery con-veyor of the machine, which delivery con-veyor is mounted on the truck to have a 90

pivotal swinging movement independent of that of the gathering conveyor, whereby the two conveyors may be relatively adjusted to

swing about their independent mountings for the purpose of adapting the machine to the 95 curved or tortuous passageways of a mine,

and to thereby provide a machine which is adaptable to the so-called "room and pillar" system of coal mining, now employed in the large majority of bituminous coal mines. 100

The loading or delivery conveyor includes an elevated horizontally extending discharge extremity which is arranged to project over an open topped mine or pit car, disposed beneath the rear end of the machine. In operation the machine is brought forward to the working face, and the gathering conveyor is moved into engagement with the coal to be gathered. The coal is then passed through the gathering conveyor and deposited within the delivery conveyor, from which unit it is finally discharged from the machine and deposited within the mine car. As these latter cars are filled, the same are drawn away from the loading machine and empty cars substituted in lieu thereof.

Referring now to the specific construction of the different units of the machine, the truck is formed to comprise a rectangular frame, consisting of parallel, longitudinally extending side members 2, united by means of a transversely extending front end member 3 and a transversely extending rear end member 4. The side members 2 are provided with journal boxes 5, in which are received front and rear axles 6 and 7 respectively, provided at their ends with wheels 8, arranged for travel over the track-way 1. It is understood that the wheels may be spaced to adapt the same to track-ways of varying gauge.

Formed with the member 3 and disposed substantially centrally thereof is a vertically extending stud 9, around which is arranged anti-friction bearings 10. Arranged to rest upon the bearings 10 and to revolve about the vertical axis of the stud 9 is a bed plate 11. This plate is shown particularly in Figures 3 and 6, and comprises a flat horizontally extending table having the main portion thereof arranged in a horizontal plane immediately above the truck and supported in connection with the truck for oscillatory movement. The forward end of the bed plate 11 is pivotally connected with the stud 9 and rests for turning movement upon the bearings 10, and the rear end thereof is supported for motion in an arc crosswise of said truck in a manner permitting the bed plate to be oscillated freely with but a minimum resistance due chiefly to friction. Thus, the rear end member 4 of the truck is formed with a horizontal shelf 12, and upon which is mounted a plurality of brackets 13, supporting therebetween rollers 14, upon the upper edges of which the rear end of the bed plate 11 rests. By the use of the anti-friction bearings 10 and the rollers 14 mechanism is provided whereby the bed plate is securely mounted upon the truck, yet permitted to oscillate freely thereover.

To permit of the swinging of the bed plate, I provide the rear central portion thereof with a vertical shaft 15, upon the lower end of which is keyed a gear or other toothed

element 16, which is disposed to mesh with the teeth of an arcuate rack 17 mounted upon the end member 4 beneath the plane of the bed plate. The rack 17 includes arcuate shaped upper and lower bars 18, which are united by means of pins 19 around which loosely rotate rollers 20, and the teeth of the gear 16 are adapted to be positioned in the pockets formed between the rollers 20. This construction of the rack precludes the presence of closed pockets and prevents the accumulation in the rack of fine coal dust, which, if present, would seriously interfere and obstruct the rotation of the gear 16 and thereby obstruct the swinging movement of the bed plate.

To revolve the gear 16, the upper end of the shaft 15 is journaled in a case 21 and has connected therewith a worm gear 22, with which meshes a worm 23, provided upon a transversely extending shaft 24. This latter shaft is journaled in bearings 25 mounted on the bed plate, and has its outer end equipped with a mitre gear 26, disposed in mesh with a similar gear 27 carried on the lower end of a vertically journaled shaft 28. A hand wheel 29 is provided upon the upper end of the shaft 28 and is located to one side of the machine so as to be within convenient reach of the machine runner, who by manipulating the wheel may readily control the positions of the bed plate. Worm gearing is used to impart motion to the gear 16 for the purpose of facilitating its operation and providing an automatic lock to prevent uncontrolled rotation of the gear 16 and thereby maintain the bed plate and the mechanism mounted thereon in desired or fixed positions of adjustment.

At its forward end the bed plate is depressed or dropped, as indicated at 30, so as to rest upon the bearing 10, and this construction is employed to provide a pivotal support for the rear end of the gathering conveyor which will be of minimum height. In my aforesaid application the bed plate occupies the same horizontal plane throughout and consequently the mechanism mounted thereon must, of necessity, be considerably higher than that disclosed herein. In the present design by lowering the bed plate at its forward end the support of the gathering conveyor is correspondingly lower and this construction materially contributes in providing a machine of but minimum height.

To support the rear end of the gathering conveyor the depressed end 30 of the bed plate is provided, as shown in Figures 6 and 7, with a pair of rigid brackets 31 which carry inwardly and horizontally extending tubular stud extensions 32, constituting trunnions. Journalized in the extensions 32 is a driven shaft 33, carrying a drive pinion 34. Journalized for oscillatory or rotary movement in a vertical plane upon the extensions 32 is a

yoke shaped support 35, terminating at its upper end in a vertical sleeve 36, upon which the upper end of the gathering conveyor is pivoted. Thus, the yoke serves as a compound pivotal support for the gathering conveyor, in that the yoke turns about the horizontal axis of the shaft 33, permitting the gathering conveyor to swing in a vertical plane, and further, said yoke, by reason of its sleeve 36, provides a support for the gathering conveyor, permitting the latter to turn in a horizontal plane about the vertical axis of the sleeve, hence the gathering conveyor is permitted to swing vertically as well as horizontally and by this construction to readily follow and adapt itself to irregularities, roughness and unevenness in the floor surface of a mine and to possess vertical flexibility for other purposes to be hereinafter described.

The gathering conveyor includes an elongated inclined frame, preferably formed from structural sheet metal, and provides an inclined intermediate portion 37, a substantially horizontally extending rear extremity 38, elevated and supported upon the yoke 35, and a substantially flat forwardly located nose extension 39 which, when the machine is in operation, rests upon the floor surface of a mine and horizontally sweeps thereover into engagement with the materials to be loaded. The rear extremity 38 is reinforced and strengthened by means of a flange casting 40, riveted or otherwise secured to the bottom of the frame and is provided with a depending tubular extension 41, arranged to receive and revolve about the sleeve 36 provided upon the upper end of the yoke 35, the lower end of the extension 41 resting upon a washer 42. The upper end of the sleeve 36 projects through an opening 43 in the bottom of the gathering conveyor frame and is provided with a bearing sleeve 44, in which rotates a vertical shaft 45. The lower end of this shaft is provided with a fixed gear 46, arranged to engage with the pinion 34, and the upper end of the shaft 45 is keyed or otherwise secured to the drive sprocket 47 of the gathering conveyor. It will be noted that the shafts 33 and 45 are merely employed to transmit power to the sprocket 47, and are not subjected to weights or loads other than that necessary to drive the sprocket and associated parts. Thus, the yoke 35, while revolving about the axis of the shaft 33, is supported upon the rigid extensions 32 of the brackets 31. Therefore, the weight of the gathering conveyor and its supporting yoke is not transmitted to the shaft 33 but upon the bed plate. Similarly, the shaft 45 rotates freely within the vertical sleeve of the supporting yoke, and since the weight of the gathering conveyor is received by the yoke, the shaft 45 does not support the rear end of the gathering conveyor.

Extending centrally of and substantially longitudinally through the frame of the gathering conveyor are chain guides 48 through which pass the endless chain or belt 49 of the gathering conveyor, the going and return runs of such chain being located in substantially coinciding horizontal planes. This chain is trained around the sprocket 47 at the rear end of the gathering conveyor and around an adjustable sprocket 50 provided upon the nose end 39 of the gathering conveyor. This chain is of staunch and durable construction to withstand the tremendous loads incident to the removing of coal from the mine face. Essentially, the chain is composed of a plurality of blocks 51 upon each of which is mounted four of the rollers 52, which are so proportioned as to pass through the guides 48 and to travel around the sprockets 47 and 50. These blocks are connected by stout, strain-tested link sections 53, which sections and the blocks 51 possess a common pitch diameter so disposed as to permit the chain to pass around and to properly mesh with the teeth of the sprockets 47 and 50. The blocks 51 project horizontally beyond the guides 48 and are equipped with flight arms 54, which travel in horizontal planes. The nose extremity 39 of the gathering conveyor is of relatively reduced diameter and includes a substantially semi-circular periphery 55, beyond which the outer ends of the flights project, as is clearly shown in Figure 5. The periphery is inclined as at 56, so that during the horizontal travel of the machine the edge of the gathering conveyor on the floor will offer but a minimum of resistance in traveling under the coal during the transverse movement of the machine, and also by reason of the inclined edge and the weight of the machine, will shear or crush coal particles lying in its path, and by the weight of the coal thereon will maintain the nose extremity of the machine on the floor of the mine, preventing any tendency thereof to climb or ride the coal. As power is imparted to the belt 49 and the conveyor is swung transversely about the vertical pivotal support at its rear end, the flights traversing the nose end of the machine are brought into engagement with the coal lying on the floor of the mine, causing the coal to be conveyed through either of the troughs 57 provided in the frame of the gathering conveyor between the central guides 48 and the outer longitudinally extending side boards 58. The belt 49 is, of course, reversible, at the will of the machine operator, and therefore coal may be carried through either of the troughs 57 in accordance with the direction in which the gathering conveyor is swung horizontally.

To impart horizontal swinging movement to the conveyor a motor 59 is mounted thereon between the spaced chain guides 48, as shown in Figures 4 and 5. This motor has its

armature shaft equipped with a pinion 60 arranged to mesh with a gear 61 provided upon a worm shaft 62, which is mounted in a gear case 63 on the conveyor. A worm 64 rotates 5 with the shaft 62 and meshes with a worm gear 65. The shaft 66 of the gear 65 is journaled in the case 63 and has one of its ends equipped with a fixed sprocket 67, around which passes an endless chain 68, which leads 10 to a second sprocket 69 mounted on a second worm gear shaft 70. This latter shaft is mounted in a case 71 and has provided thereon a worm 72, which meshes with a gear 73, both of which being mounted in the case 71. 15 The gear 73 is fast to a quill 74, journaled for rotation in bearings 75 and around a stationary shaft 76. Fixed to rotate with the quill 74 and revolve in a vertical plane is a pocket sheave or drum 77. An ordinary anchor chain 20 78 has its links arranged to be received within the pockets of the sheave 77, so that when the latter is rotated the gathering conveyor will be moved laterally in the direction of the chain. As shown in Figure 2, the outer 25 ends of the chain 78 are secured to jacks or other lateral anchors 79, which are stationarily mounted in any suitable manner at each side of the gathering conveyor, and to which the ends of the chain 78 are fastened. 30 It will be appreciated that by the rotation of the sheave 77 and the fact that the chain 78 is immovable, lateral horizontal swinging movement will be imparted to the conveyor. Hawse guides 80 are carried by the frame of 35 the conveyor to guide the chain properly around the sheave 77 and prevent entanglement thereof in the various parts of the machine adjacent thereto. By this construction the mere operation of the controller for the 40 motor 59 is sufficient to impart horizontal travel to the gathering conveyor. Furthermore, the machine will be locked in any position of horizontal adjustment by reason of the worm gearing employed in reducing the 45 speed of the motor 59.

The chains 49 and 78 are of heavy durable construction so as to be adapted to the severe service to which they are placed and it will be noted that the link sections 53 used in the 50 chain 49 permit the chain to flex in two directions, horizontal as well as vertical, thus adapting the belt to the configuration of the gathering conveyor frame. While the chain 49 is of very substantial construction, nevertheless by reason of wear and use the same is 55 bound to stretch somewhat, and slack can be kept out of the chain by adjusting the nose sprocket 50. This is accomplished by mounting said sprocket in a sliding bracket 81, 60 which is movable horizontally and longitudinally and between the forward ends of the chain guides 48. One way of accomplishing this adjustment is to mount upon the conveyor a screw 82, upon which is threaded a 65 nut 83, which is rotatably received in a wall

or partition 84 provided in the bracket 81. By rotating the nut it will be apparent that the bracket 81 may be moved longitudinally of the conveyor. Supporting or auxiliary binding devices 85 are also used in connection 70 with the bracket 81 to maintain its fixed positions of adjustment. Covering the adjustable sprocket is a guard plate 86 which may also be used in the capacity of a platform, permitting an operator to stand thereon and by wielding a pick or the like to loosen such materials that have not been properly shot down upon the floor of the mine during the operation of shooting or loosening the materials preliminary to the loading thereof. 75

It will be understood that in coal mining particularly, coal is first prepared for the loading machine by a crew of men who shoot or blast the coal down in a loosened, gatherable mass upon the floor of the mine, after 80 which operation the machine is placed into gathering relation to this shot down coal. Sometimes, it happens after this shooting that the coal is not entirely freed from its native bed, and for this reason it is necessary 85 at intervals to pick that portion of the coal down which is partially shattered or held in clinging engagement with the solid coal. The machine is so constructed as to handle coal of any size, from slack to large lumps, but 90 particularly the machine is adapted to mine lump coal, which is of greater commercial value than the finer slack grades. The lump coal can be obtained by proper preliminary shooting of the coal. This involves the use 95 of just sufficient powder or other explosive to loosen the coal and free it from the solid, but frequently this operation is not properly carried out, leaving as a result large lumps of coal more or less in the solid, which the machine is obliged to attack and remove. For 100 this reason the machine has been substantially and durably constructed throughout its entire design, but particular care has been used in the design of the forward end of the gathering conveyor so that the latter will not 105 be injured or require repairs by reason of being forced into solid coal so frequently encountered by present methods of shooting coal into large lump formation. 110

When it is desired to transport the machine over the trackway 1 from one working location to another, which must be performed about ten times to each shift of eight hours, the forward end of the gathering conveyor is 115 removed from the floor of the mine and is mounted upon a pony truck 87, so that the gathering conveyor will possess but a minimum of tangential projection when rounding sharp curves of a mine and will be readily adapted to narrow rooms and entries. To 120 permit this to be performed quickly with but a minimum of time, considering the weight of the machine, I provide the underside of the gathering conveyor frame with inclined 125

guides 88, constituting a track-way. The pony truck 87 is constructed as shown particularly in Figures 14 and 15 and includes spaced transversely extending axles 89 carrying wheels 90 at the outer ends thereof, which wheels are grooved as shown at 91, for the reception of chains 92. These chains are, as shown in Figure 1, attached to the conveyor frame and are employed to hold 10 the pony truck suspended beneath said frame during the period of operation when the machine is loading coal. However, when adapted for transportation the pony truck is lowered on the track-way 1, as shown in 15 Figure 4, and its wheels are blocked to prevent sliding or skidding thereon. Then, arranged upon the axles is a bed frame 93 which carries bearings 94 for the reception of a horizontal shaft 95, and rotatable about 20 this shaft is a pair of rollers 96, and disposed between said rollers is a socket 97. After the wheels of the pony truck have been blocked the loading machine is moved rearwardly along the track-way until the guides 25 88 engage with the rollers 96, and by reason of the inclination of the guides and the fact that the pony truck is blocked against rearward movement, further rearward movement on the part of the loading machine results in the 30 elevation of the gathering conveyor, lifting its forward nose extremity from the floor of the mine and finally positioning the same well above and clear of the rails constituting the track-way 1. Continued rearward movement of the machine is effected until a king 35 pin 98 carried by the gathering conveyor in a vertical bracket 99 has its lower end engaged by a lip 100 projecting upwardly from the bed frame 93 adjacent the socket 97. When this registration is reached the king 40 pin 98 is dropped or lowered until the lower extremity thereof is received within the socket 97, thereby establishing a swivel connection between the gathering conveyor and the pony truck. The rollers 96 facilitate 45 travel of the gathering conveyor over the pony truck, and further, after the king pin has been lowered the said rollers permit free turning movement of the gathering conveyor 50 relative to the pony truck. When the machine has been transported to a new working location, the forward or nose extremity of the gathering conveyor is moved to a position in advance of the forward terminals of the 55 track-way, whereupon the king pin is elevated, freeing the gathering conveyor from connection with the pony truck. Then by slightly moving the machine forwardly the inclined portions of the guides 88 press upon 60 the rollers 96, causing rearward movement of the pony truck and consequent lowering movement of the nose extremity of the gathering conveyor, which is finally deposited upon the ground and is ready for operation. 65 A bumper 101 is formed with the bed frame of the pony truck so that when the gathering conveyor rapidly descends and forces the pony truck sharply backward the movement of the pony truck will be curtailed by the engagement of the bumper 101 with the forward part of the main truck. 70 A large part of machine mining or loading is performed on curves, and for this reason it is impractical to discharge coal directly from an elongated gathering conveyor directly into a pit car for the reason that if the gathering conveyor is to have a pivoted sweep movement through an arc whose chord measures substantially 20 feet, the rear or the discharge end of the machine 75 will be swung so as to uncover the open end of the mine car. Therefore, practical tests have convinced me that a second or delivery conveyor is essential to provide the necessary flexibility and position for transferring coal from a working face to a mine car on a curve. 80 To this end I employ a delivery conveyor designated generally by the letter B, which consists of a structural steel frame having the forward end thereof formed to provide a wide and deep hopper 102, which is arranged immediately beneath the rear or discharge end of the gathering conveyor and in registration with the open flight space formed 85 between the discharge ends of the gathering conveyor troughs 57. The hopper is provided, as shown in Figure 2, with the flaring side walls 103, which have their forward ends recessed or cut away as at 104 to receive the rear swinging end of the gathering conveyor, and to permit said conveyor to swing through a relatively wide arc without engaging or interfering with the walls of the hopper. The recessed portions 104, however, are adapted to be filled by means of removable plates 105, which may be slidably adjusted to open or obstruct the recesses. When moved to an active position covering said recesses the plates 105 serve as barriers to prevent coal thrown tangentially from the rapidly 90 revolving flight arms 54 of the gathering conveyor from being thrown to the ground and to direct such coal down toward the upwardly inclined bottom 106 of the hopper. The extreme forward end of the hopper is provided with a throat 107 in which the supporting yoke 35 is received and permitted to vibrate. The hopper terminates upwardly and rearwardly in a horizontally extending discharge extension 108 of elongated form 95 and arranged to project rearwardly beyond the truck of the machine so as to overhang a mine car 109, as shown in Figure 1. To convey coal through the delivery conveyor a pair of longitudinally extending transversely spaced endless chains 110 is employed, which chains are connected by means of transversely extending flights 111 so arranged that the going sections of the chains will cause the flights 111 to travel over the bottom 106 of 100 105 110 115 120 125 130

the delivery conveyor, moving the coal rearwardly in a draft direction through the machine. One of the features of the present invention consists in dropping the lower forward end of the hopper through an opening 112 in the bed plate 11, whereby the lower portion of said hopper is brought within the confines of the side frames of the truck. In fact, the hopper is dropped so that its lowest portion is within about 3 inches of the tops of the rails forming the track-way 1. This construction is in contrast with that disclosed in the application above referred to wherein the hopper is mounted above the bed plate rather than partially beneath it. Manifestly, the construction disclosed in this application permits of a material reduction in the height of the machine, enabling the same to operate in the low seams of coal above mentioned.

To support the forward lower end of the hopper the bed plate is provided with a pair of depending brackets 113, which receive a fixed foot shaft 114 extending transversely through the lower end of the hopper, and loosely mounted for rotation upon the shaft 114 is a pair of sprockets 115 around which the chains 110 are trained. The power shaft of the loading conveyor is located at its rear end and is designated by the numeral 116, and power is imparted to the same by transmission devices hereinafter described.

Arranged upon the upper surfaces of the bed plate to one side of the delivery conveyor frame is an electric motor 117 of a reversible type, although compressed air can be used in gaseous mines. This motor is provided with a pinion 118, Figure 6, meshing with a gear 119 fixed to a back gear shaft 120, suitably journaled in connection with the bed plate of the machine. The shaft 120 extends transversely across the machine beneath the delivery conveyor and has its other end arranged for rotation within a transmission housing 121 mounted upon the bed plate on the opposite side of the delivery conveyor frame as regards the motor 117. As shown in Figure 11 the shaft 120 has keyed thereon as at 122, a hub 123, which constitutes the driving member of a combined slip and cut-out clutch 124. Loosely arranged for rotation about the driving member 123 is a driven member 124, and disposed between the driving and driven members is a multiplicity of friction discs 125, alternate sets of which are keyed to the driving member and to the driven member, the arrangement being such that when the said discs have their flat sides brought into frictional relationship with one another power will be imparted from the driving member to the driven member, but upon the overloading of the driven member, the discs will slip relatively to prevent injury to the driving units of the machine associated with the clutch.

To conveniently control the operation of

the clutch the driven member has keyed thereto a frictional pressure plate 126 and a head 127. The head carries a plurality of pivoted bell crank levers 128 to the shorter arms of which is connected a plurality of rollers 129, so arranged as to press upon the plate 126 and to thereby impart pressure to the discs 125 when said levers 128 are oscillated in a predetermined direction. The longer arm of the bell crank levers are provided with heads 130 which are positioned within a clutch sleeve 131, loosely mounted upon one end of the shaft 120. A throw yoke 132 is provided within the housing and is manually operated to slide the sleeve 131 on its supporting shaft. Obviously, by the manipulation of the yoke 132 the bell crank levers 128 may be rocked about their pivots so as to apply or remove pressure from the disc assembly 125, thereby governing at will the impartation of power from the driving to the driven members of the clutch.

Rotatable with the driven member 124 of the clutch is a sleeve extension 133, with which is formed a pinion 134, arranged to engage with an enlarged gear 135 fixed to rotate with a jack shaft 136 journaled in the housing 121. This latter shaft is provided with a fixed pinion 137 arranged to mesh with a gear 138, provided upon the upper end of the longitudinally extending inclined shaft 139. The lower end of this shaft is journaled within a bearing 140, Figure 6, carried in connection with the forward end of the bed plate and is equipped with a pinion 141 meshing with a similar pinion 142 on the outer end of the shaft 33. It will be apparent that by this construction the power of the motor 117 may be readily imparted to the gathering conveyor, and by reversing the direction of rotation of the armature shaft of said motor, the direction of travel of the gathering conveyor belt may be governed at will. Further, by the reduction gearing set forth the speed of the motor may be appropriately stepped down to conform to the required operating speed of the gathering conveyor. It will be understood that the pinions 141 and 142 are to be suitably encased and operated in an oil bath so as to be protected from dust and grit. Similarly the same construction is to be provided in connection with the pinion 34 and the gear 46. As shown in Figures 6 and 7, one of the side frame members *a* of the truck is provided with a pocket 143 for the reception of the pinion 141, which pocket provides adequate space in permitting of the horizontal swinging movement of the bed plate. It will be understood that by operating the yoke 132, the runner of the machine has instant control of the operation of the gathering conveyor, and furthermore, if said gathering conveyor is overloaded, the clutch 124 is of such construction and may be set so that the same will slip, preventing injury

to the gathering conveyor and the power transmission device associated therewith.

To drive the delivery conveyor, the back gear shaft 120 is provided with a sprocket 144 over which is trained an endless chain 145, which also passes over a sprocket 146 provided upon a rotatable quill 147, Figs. 12 and 13, which is arranged for rotation within a housing 148 carried in connection with the delivery conveyor frame. The housing 148 includes stud shafts 149 and 150, arranged in parallel order and upon the former of which the quill 147 is supported for rotation. Also carried by the quill 147 and fixed to rotate therewith is a second sprocket 151 and a gear 152. Trained over the sprocket 151 is an endless chain 153 which leads to a second sprocket 154 loosely rotatable upon the shaft 150. The gear 152 is arranged to mesh with a second gear 155 loosely rotatable upon the shaft 150. As shown particularly in Figure 12, the sprocket 154 and the gear 155 are provided with complementary clutch jaw faces 156, and between these faces there is disposed an automatically shiftable sprocket 157, whose hub is formed on opposite sides with clutch faces 158, arranged for engagement with the clutch faces of the gear and sprocket 155 and 154 respectively. Passing around the sprocket 157 is a chain 159, which leads to the drive sprocket 160 provided upon the power shaft 116 at the rear end of the delivery conveyor. By the automatic reverse gear mechanism described a means is provided whereby the delivery conveyor is driven in but one direction and the gathering conveyor in two directions from a common source of power. The motor 117 is of the reversible type, and consequently with the operation of the reverse drum of its controller the direction of turning movement of the armature shaft of said motor may be controlled at the will of the operator and consequently the direction of travel of the gathering conveyor chain is correspondingly regulated. However, the delivery conveyor is of a non-reversible character, and by the gearing described I am enabled to drive the delivery conveyor in but one direction from the motor 117 regardless of the direction of rotation of the armature shaft of said motor, whenever said motor is running. Furthermore, this is accomplished without manual adjustments as it is a cardinal principle in the design of the machine to control its various units by means of electric controllers for the motors, and to eliminate the hand setting of clutches or other mechanical features of control which are likely to be abused by the mechanically inexperienced operatives of an ordinary mine crew.

It will be understood that in the present instance the loading conveyor chain is kept running in a draft direction by the automatic shiftable sprocket 157, whose clutch faces 158 are reversely disposed and adapted

to the complementary faces of the sprocket and gear 154 and 155. Thus, as shown in Figure 12, if the sprocket 157 is being driven by the gear 155 and the direction of rotation of the motor 117 is reversed, the direction of rotation of the gear 155 will then be reversed. Due, therefore, to the inclined jaw surface, the sprocket 157 is shifted out of engagement with the gear 155 and moved over a sufficient distance so that its opposite clutch face will be engaged with the complementary jaw face provided upon the sprocket 154, which will then be rotated in the desired direction. A spring 161 is used to provide relief for the teeth of the clutch faces in the event that the tips of the teeth first come in contact with one another during the shifting of the sprocket 157.

To support the rear overhanging end of the delivery conveyor there is provided a pair of tubular standards 162, as shown more particularly in Figure 10. These standards are of telescopic construction and are extensible or contractable so as to effect the raising and lowering of the delivery end of the loading conveyor. This is effected by forming each of the standards to comprise a lower cup shaped section 163 consisting of two sections threaded together, which is pivoted as at 164 to the bed plate. Arising within this section and formed rigidly therewith is a screw 165. Arranged to be received within the section 163 is an adjustable section 166, which has its lower end provided with a nut enlargement 167 arranged to receive the screw 165. The upper end of the section 166 at one side is provided with a hand wheel 168, by means of which the sections 166 of both standards may be operated. The section equipped with the hand wheel 168 is also formed with a sprocket 169, around which passes a chain 170, leading to the complementary sprocket 169 formed on the other section 166. Thus, by rotating the single hand wheel 168 uniform movement may be imparted to both sections permitting of their revolution about the screws 165 and the consequent expansion or contraction of the standards 162. The upper ends of each of the sections 166 are provided with sockets for the reception of loosely receivable pins 171, which are collared as at 172 to rest upon anti-friction bearings 173, the extreme upper ends of the pins 171 being pivotally connected as at 174 with the frame of the delivery conveyor. Thus, the weight of the delivery conveyor at its rear end rests upon the bearings 173, permitting the sections 166 to be revolved manually and uniformly to effect adjustment in the height of the delivery end of the loading conveyor. The standards may be connected by cross braces 175, which impart rigidity thereto. Further, by pivotally connecting the upper and lower ends of the standards with the frame of the delivery conveyor and the bed 130

plate respectively the standards are adapted to the pivotal adjustment of the loading conveyor. In this respect it will be observed that the chain 145 is trained over an idler 176 and occupies a position permitting of the relative adjustment between the delivery conveyor and the bed plate without in any way affecting the driving of the sprocket 146. In conjunction with the rollers 14, the side members 2 of the truck are provided with outwardly extending ears 177, which carry rollers 178 arranged beyond the confines of the truck proper. The rollers 178 act in conjunction with the rollers 14 for the purpose of supporting for motion the free end of the bed plate when the latter is swung to an extreme angular position, which position may be, at least, 15 degrees beyond the longitudinal center line of the truck.

In order that the loading machine may be self propelled so as to travel over the track-way 1 or to force itself into the coal to be gathered, there is provided a propelling mechanism which, as shown in Figure 9 particularly, consists of a reversible electric motor 180. This motor is mounted on a shelf 181 arranged at the extreme front end of the truck and rigidly connected with the side members 2 and the front end member 3. The armature shaft 182 of the motor is equipped with a pinion 183, which meshes with a gear 184 rigidly rotatable with a quill 185 on a stud shaft 186. The shaft 186 is journaled in connection with a casing 187 employed to house the speed reducing gearing of the self propelling mechanism. Rotatable with the quill 185 is a pinion 188, which meshes with an idler pinion 189, the latter in turn meshing with a gear 190 fast on a worm shaft 191. On this shaft is formed a worm 192, arranged between thrust bearings 193, in which the shaft 191 rotates. The worm 192 is employed to drive a worm gear 194, arranged in a vertical plane below the worm 192. Driven by the worm gear 194 is a shaft 195, which extends laterally of the shelf 181, and is rotatable in an elongated bearing 196, carried in connection with a worm gear housing 197. Slidably keyed upon the outer end of the shaft 195 is a clutch member 198, which may be manually operated so as to be thrown into and out of driving relation with a sprocket 199, loosely rotatable about the shaft 195. Trained around the sprocket 199 is a chain 200, which leads to a sprocket 201 mounted on the front axle 6. A second sprocket 202 is mounted on the other side of the axle 6 in line with a similar sprocket 203 on the rear axle 7, a chain 204 connecting the said latter sprockets so that when the motor 180 is energized power will be imparted to both axles, and since the weight on the truck has been equally distributed, all four wheels are equally effective as drivers in effecting the self propulsion of the machine. By providing worm gearing in the

speed reduction connected with the motor 180, an automatic lock is provided for maintaining the machine braked or locked on a track-way, even when the latter is on a decided grade. This feature is particularly useful when the track-way is pitched or on an angle with respect to the horizontal.

In the operation of the machine the track-way 1 is laid through a mine room up to substantially the working face, which face is then drilled and shot so that the solid coal will be disrupted from its native bed and blasted down upon the floor of the mine in a shattered, semi-loose gatherable mass. The percentage of lump coal in this mass is governed by the methods of blasting or drilling the coal, and the quantity of explosives used in the blasting process. However, the machine has been so designed as to withstand the strains and stresses of poor shooting so as to handle either large lumps of coal or the finely shattered slack coal. Following the shooting operation the machine is transported over the track-way 1 up to the working face. The gathering conveyor is then removed from the pony truck 87, to permit the front end of the gathering conveyor to drop upon the mine floor, and the pony truck is supported by chains beneath the inclined portion of the gathering conveyor frame, as shown in Figure 1, so as to be out of the way and avoid interference with the manipulation of the gathering conveyor. Jacks or lateral anchors 79 of a quickly removable nature are then set up independently and to each side of the gathering conveyor, and to which the ends of the chain 78 are connected. Either after or before the setting of the jacks, the loading machine as a whole is advanced by the propelling mechanism forwardly on the track until the nose end of the machine is forced into and buried beneath the mass of coal to be gathered. The motor 117 is then operated and the clutch 124 thrown in so that power will be imparted to the belts and both the gathering and delivery conveyors. This causes the flight arms 54 to revolve about the nose sprocket 50, coming into contact with the coal so as to remove the latter from the floor and selectively convey the same through either of the troughs 57, finally discharging the coal from the upper ends of the troughs and depositing the same within the hopper 102. In the bottom of the hopper the coal is engaged with the flights 111 and carried rearwardly of the delivery conveyor and finally discharged into the mine car 109 placed beneath the discharge extension 108 of the delivery conveyor. This process continues until the car 109 is filled and then the machine is shut down momentarily permitting the car 109 to be replaced by an empty one. As a part of the gathering operation of the machine the sheave 77 is rotated through the transmission described by the motor 59, and

this causes the gathering conveyor to sweep right and left in a horizontal plane across the full width of the mine room, enabling the machine to gather coal from the floor of the mine across the full width of the room or 5 other place wherein the machine is working. The gathering conveyor is mounted on the yoke 35 so as to possess an operating arc of substantially 170 degrees, and similarly, the delivery conveyor is mounted to possess a 10 swinging movement of substantially 30 degrees. These movements produce a machine of sufficient flexibility to meet the requirements of the room and pillar system of mining coal, which is the system most commonly 15 used and wherein coal must be loaded on curved track-ways of short radii to be successful. While extreme flexibility is provided, nevertheless there exists at all times a 20 registering relationship between the discharge end of the gathering conveyor and the receiving hopper of the delivery conveyor. This is mainly due to the registration of the 25 vertical pivots for the gathering and delivery conveyors, reference being had to Figure 3, wherein it will be noted that the stud 9, which is the vertical pivot for the delivery conveyor, is in registration with the sleeve 36, constituting the vertical pivot for the 30 gathering conveyor. It is due to this fact and also to the shape of the hopper sides that the conveyors may be adjusted relative to each other without spilling coal in effecting the transfer of the latter material from the 35 primary to the secondary conveyors.

What is claimed is:

1. In a loading machine, a wheeled truck, a bed pivotally bearing at its forward end upon said truck and at its rear end supported 40 for motion in an arc cross-wise of said truck, an inclined conveyor, means for pivotally suspending the forward lower end of said conveyor beneath said bed whereby the lower end of said conveyor is within the plane of said truck, and a support between an elevated portion of said conveyor and said bed.

2. In a loading machine, a wheeled truck, a bed pivotally bearing at its forward end upon said truck and having its rear end supported 45 for motion in an arc cross-wise of said truck, an inclined conveyor having the forward lower end thereof arranged to project through an opening provided in said bed and means for pivotally connecting the forward lower end of said conveyor to and beneath said bed.

3. In a loading machine, a wheeled truck, a bed pivotally bearing at its forward end upon said truck and having its rear end supported 50 for motion in an arc cross-wise of said truck, an inclined conveyor having the forward lower end thereof received within an opening provided in said bed, and means for supporting the lower end of said conveyor from beneath said bed.

4. In a loading machine, a truck, a horizontally swinging bed on said truck, an inclined conveyor having the lower end thereof connected to said bed beneath the horizontal plane of the latter, the upper end of said conveyor being disposed above said bed, and a driving motor for said conveyor mounted on said bed to one side of said conveyor, and power transmission devices between said motor and said conveyor on the other side of said bed. 73

5. In a loading machine, a truck, a horizontally disposed bed pivotally bearing at its forward end upon said truck and at its rear end supported for movement in an arc cross-wise of said truck, an inclined conveyor mounted to swing with said bed and having the forward lower end thereof pivotally connected to and suspended from the under side of the bed, whereby the lower end of said conveyor lies in the horizontal plane of said truck, supports between the swinging end of said bed and an elevated portion of said conveyor, a motor for said conveyor mounted on said bed to one side of the conveyor, and power transmission devices between said motor and said conveyor. 80

6. In a loading machine, a wheeled truck, a bed plate pivotally bearing at its forward end upon said truck and having its rear end supported for motion in an arc cross-wise of said truck, an inclined conveyor having the lower end thereof positioned within an opening provided in said bed plate, bearings depending from said bed plate adjacent the lower end of said conveyor, means for pivotally mounting the lower end of said conveyor in connection with said bearings, and supporting means between the free swinging end of said plate and the relatively elevated end of said conveyor. 95

7. In a loading machine, a truck including a pair of longitudinally spaced wheeled axles, a horizontal bed plate pivotally bearing at its forward end upon the frame of said truck 110 at a point between said axles, the rear end of said bed plate being supported from motion in an arc cross-wise of said truck and to the rear of the axle, an inclined conveyor having the forward loading end thereof pivotally supported by and beneath said bed plate at a position between said axles, and an operating motor for said conveyor mounted on the swinging end of said bed plate. 115

8. In a loading machine, a truck including a pair of wheeled axles, a horizontally disposed bed, a pivotal connection between the front end of said bed and said truck situated between said axles and in the plane of the truck, means for supporting the rear end of said bed for motion in an arc cross-wise of said truck, an elongated inclined gathering conveyor, a pivotal support for said conveyor carried by said bed and arranged in registration with the pivotal connection be- 125

tween said bed and truck, an inclined delivery conveyor arranged on said bed in receiving relation to said gathering conveyor and supporting means for the lower end of 5 said delivery conveyor carried by and arranged beneath the plane of said bed.

9. In a loading machine, a truck including a pair of spaced wheeled axles, a horizontally disposed bed, a pivotal connection between 10 said bed and truck disposed between said axles and arranged within said truck below the top of the latter, an elongated inclined gathering conveyor, a pivotal support for the upper or rear end of said conveyor pivotally carried 15 by said bed and disposed in vertical registration with the pivotal connection between said bed and truck, an inclined delivery conveyor projecting rearwardly from said truck and having the forward receiving end thereof disposed in registration with the discharge end 20 of said gathering conveyor, a pivotal connection between the forward end of said delivery conveyor and said bed, arranged in the horizontal plane of said truck, and an operating 25 motor for said delivery conveyor mounted on said bed.

10. In a loading machine, a truck including the frame, having a pair of wheeled axles, an elongated inclined gathering conveyor arranged 30 to extend in advance of said truck, a pivotal support for the upper end of said gathering conveyor mounted in connection with said truck frame, said support being arranged between said axles, a delivery conveyor having the forward end thereof disposed in receiving relation with the discharge end of said gathering conveyor, and means 35 for mounting the forward end of said delivery conveyor within and below the top of 40 said truck frame and between said axles.

11. In a loading machine, a truck including a pair of longitudinally spaced wheeled axles, an elongated inclined gathering conveyor, having the upper end thereof arranged above 45 said truck, a pivotal support for the rear end of said gathering conveyor arising from said truck between said axles, an inclined delivery conveyor extending rearwardly from said truck and having the forward end thereof disposed in receiving relation with respect to 50 the rear end of said gathering conveyor, and supporting means between the lower forward end of said delivery conveyor and said truck situated between said axles and in a plane beneath the top of the truck.

12. In a loading machine, a truck including a pair of wheeled axles, a horizontal bed pivotally bearing at its front end upon said truck at a position between said axles, means 60 for supporting the bed at its rear end for motion in an arc cross-wise of said truck, an elongated inclined gathering conveyor having its rear end arranged above said truck, a pivotally mounted support for the rear end 65 of said gathering conveyor carried by said

bed plate and disposed in registration with the pivoted end of the latter, a delivery conveyor having the forward end thereof disposed in receiving relation beneath said gathering conveyor, suspended supporting means connecting said delivery conveyor with 70 said bed at a position between said axles and beneath the top of the truck, a motor on the swinging end of said bed, and power transmission devices between said motor and conveyors. 75

13. In a loading machine, a wheeled truck, a bed pivotally bearing at its forward end on said truck and having its rear end supported for motion in an arc cross-wise of the truck, 80 an elongated inclined gathering conveyor having its rear end arranged over said truck, a pivotal support for said conveyor carried by said bed and arranged in registration with the pivotal connection between the bed and truck and supporting means depending from 85 said bed and lying within the plane of said truck and adapted for the reception of any one of a plurality of interchangeable delivery conveyors, whereby the machine is adapted 90 to coal seams of varying thicknesses. 95

In testimony whereof I affix my signature.
NORTON A. NEWDICK.
